UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINOTYPE-MACHINE.

No. 890,178.

Specification of Letters Patent. Patented June 9, 1908.

Application filed February 20, 1908. Serial No. 416,873.

To all whom it may concern:

Be it known that I, JOHN R. ROGERS, of borough of Brooklyn, county of Kings, and State of New York, have invented a new and useful Improvement in Linotype-Machines, of which the following is a specification.

My invention has reference to means intended more particularly for use in linotype machines which contain circulating matrices, to effect the distribution or separation of the matrices.

My invention is applicable either for the separation of matrices of different fonts bearing the same character, so that they may be directed to different magazines, or to the separation of matrices belonging to different fonts according to font, in order that they may be delivered to different distributing mechanisms, and the object is primarily to provide an extremely simple mechanism which shall be positive in its action, and without moving parts.

To this end it consists broadly in a stationary deflector or separator, having reversely inclined surfaces arranged as hereinafter described and adapted to coöperate with suitably notched matrices in such manner that a matrix delivered endwise to the separator will be deflected sidewise to the right or left into one channel or another, according to the nature of the slots in the matrix.

My invention also includes matrices having their surfaces differently notched or cut at one end, in order that they may coöperate with the stationary deflector in order to pursue one path or another, as demanded.

In the drawings.—Figure 1 is a longitudinal vertical section through my distributing mechanism in a form adapted for separating matrices of different fonts bearing the same character, and effecting their delivery to the magazines in which they are respectively stored. Figs. 2 and 3 are vertical sections through one of the distributing devices, showing the manner in which the matrices of different forms are deflected to the left and right respectively. Fig. 4 is a vertical section on the line 4—4, Fig. 1. Fig. 5 is a horizontal section on the line 5—5, Figs. 1 and 4, looking in a downward direction. Figs. 6 and 7 are side views of two matrices containing the same character but belonging to different fonts. Fig. 8 is a perspective view

through one of the distributors, with the matrix-guiding tubes or conductors connected therewith. Fig. 9 is a side elevation of a mechanism for separating matrices of four fonts, and delivering them to a series of distributors by which they are in turn distributed to the channels of four magazines. Fig. 10 is a cross-section on the line 10—10, Fig. 9. Fig. 11 is a perspective view of one of the distributors or deflectors, with a portion of the surrounding tubes or conductors broken away. Figs. 12 and 13 are vertical cross-sections of the same, showing the manner in which matrices differently notched are deflected to the left and right respectively. Fig. 14 is a perspective view of one of the matrices.

In order that the remainder of the mechanism shown may be more readily understood, I will first describe one of the separators or deflectors, and the manner in which it separates the passing matrices into two groups.

The separator is intended to deal with matrices of the well known Mergenthaler form, such as shown at A, A', in Figs. 6 and 7, or with matrices of any other form, which are adapted to receive the notches herein-after described.

Each of the matrices shown, consists of a flat plate of a generally rectangular form, with distributing teeth *a* in the upper end, and with the character or matrix proper *a'* in one edge, as usual. The matrix is also formed as usual, with four ears at the respective corners, projecting edgewise beyond the body of the matrix, these ears serving to guide the matrices through the magazine and to align them in the casting position. All the matrices employed will be alike as to their external form and dimensions, but they will vary in thickness to correspond with the characters with which they are provided. In adapting these matrices for use in my distributing mechanism, I provide them in the lower ends with vertical notches differing in number, or arrangement, or both, as between matrices of different fonts, or matrices which, for other reasons, are to pursue different paths. For example, in Fig. 6 the matrix A, to be stored in one magazine of the machine, is provided with a single central notch *a²* in its lower end. The matrix A', shown in Fig.

7, and intended for storage in another magazine, is provided with two notches a^3 on opposite sides of the same.

The number of slots and their relative arrangement may be widely varied at will according to the number of separations to be effected, the only requirement being that each matrix shall present an unbroken or uncut surface to coöperate with the surface or surfaces of the deflector inclined in one direction as hereinafter described, and that it shall also be slotted or cut away in such manner as to avoid deflecting surfaces inclined in the reverse direction.

15 It will be observed that the slots extend through the matrices transversely from one side face to the other, and that they leave the matrices of a symmetrical and generally rectangular form, so that they may be controlled and used in the machine in the same manner as ordinary commercial matrices.

20 A typical separator or deflector adapted to coöperate with the matrices shown in Figs. 6 and 7, is illustrated in Fig. 8. It consists of a stationary base portion B, provided with 25 three rigid upright tongues b, b, b', adapted to enter the respective notches in the matrices as the latter are permitted to descend endwise toward them.

30 It will be seen that the tongues b, b; have their top surfaces inclined downward toward the channel on the right side of the separator, while the intermediate tongue has its upper surface inclined in the reverse direction, or 35 toward the channel on the opposite side of the separator.

It is to be observed that the oppositely inclined surfaces of the respective tongues are overlapped, or in other words, arranged to 40 cross or intersect a central vertical plane. One advantage of this arrangement lies in the fact that the matrices of different thicknesses descending in the same path, may be separated by a sidewise, as distinguished 45 from an edgewise movement, and by a very slight deflection of the matrices from their original paths.

If the matrix A is delivered endwise to the 50 separator, the solid or uncut portions of its lower end will ride on the inclined upper surfaces of the tongues b, which will serve to deflect the descending matrix to the left, in the manner shown in Fig. 2, and on the left-hand in Fig. 4. During this action, the tongue b' 55 enters the notch a^2 and is inactive, the slot being formed for the purpose of affording clearance for the tongue b', so that it will have no effect upon those matrices which are adapted for deflection to the left.

60 If the second matrix A' is delivered downward to the separator, the solid or uncut portion at its center will ride upon the inclined surface of the tongue b' and the matrix will be deflected to the right, the tongues b at

such time passing idly through the slots a^3 , 65 as shown in Fig. 3.

It is to be noted that the slots are formed for the purpose of avoiding any action or influence on the part of those inclined surfaces which are not, for the moment, in use. 70 By providing the separator with the surfaces reversely inclined, and providing the matrices with slots so arranged that whenever a matrix rides upon a surface inclined in one direction, it will, at the same time, avoid 75 contact with the surfaces inclined in the reverse direction, I am enabled to effect the speedy certain separation of the matrices into two groups or sets as they pass the separator.

80 The surfaces forming the upper ends of the slots are preferably inclined, as shown, but this is not a necessary feature. It is recommended, however, because the necessary clearance can be given by the removal 85 of less metal than would otherwise be required.

Referring now to the manner in which my separator may be used to deliver matrices from a single distributer to two magazines, 90 attention is directed to Figs. 1 to 8 inclusive. C and C' represent two inclined channeled magazines in which the matrices are to be stored. These magazines may be of the ordinary Mergenthaler construction shown in 95 U. S. Letters Patent #436,532, or of any other suitable construction. D represents a distributer of the ordinary Mergenthaler type, designed to separate the matrices according to letter. It consists of a horizontal 100 fixed bar provided with longitudinal permuted teeth on the lower edge to engage the teeth of the matrices and hold them in suspension as they are moved along the bar, until they arrive at the points at which they are to be discharged, the movement being effected by means of screws E, E, in a manner well understood in the art. The matrix fonts carried in the respective magazines will contain the same characters, but in different sizes. or forms. For example, a 105 Roman A will be carried in a channel of the upper magazine, and a Gothic A will be carried in the corresponding channel of the lower magazine. Both of these characters 110 will be released from the distributer-bar D' at the same point, one at a time. For the purpose of conducting the matrices thus delivered to the different magazines in which they belong, I provide a series of conducting 115 tubes F, such as shown in Figs. 4, 5 and 8, each made at the upper end in the form of a single tube to receive the matrices falling from the distributer, but divided midway of its length into two tubes F' and F'', which communicate with the respective magazines. At the 120 point where the conductor is forked or divided, I locate the separator B. All the 125

matrices falling from the one point on the distributor-bar, regardless of the magazine in which they belong, are received upon the separator B, by which they are deflected, 5 according to form, right and left into the lower ends F', F², from which they pass into the respective magazines. A matrix belonging in the upper magazine, falling from the distributor through the passage F, is deflected to the left, and passes through the 10 branch F'; while a matrix belonging in the lower magazine pursues the same path until it reaches the separator B, when it is deflected to the right and caused to pass 15 through the conductor F². It will be observed that the lower ends F' and F² are deflected laterally, and that one terminates directly over the other in the same vertical 20 plane.

20 I believe it to be new in the art to separate matrices descending in a common path, by deflecting them laterally, that is to say, side- 25 wise to the right and left, and also new to then bring them back after separation into the same vertical plane so that they may be 30 directed into corresponding channels of the upper and lower magazines.

I will now describe the manner in which my separator is utilized to effect the separation of matrices belonging to four fonts, and to deliver the same to a corresponding number of distributors for returning the individual matrices to the corresponding channels in the several magazines.

35 Referring to Fig. 9, D' represents a short distributor-bar to which the matrices are successively presented by the ordinary devices used in commercial Mergenthaler machines. This bar is adapted to release all the 40 matrices regardless of letter and font, and permit them to descend to a common point through a guiding throat H to a separator B, similar to that shown in the preceding figures. The lower ends of the matrices are 45 notched in the manner already described, and the separator B serves to deflect them right and left, those of two fonts being deflected to the right, and those of the other two fonts being deflected to the left.

50 H' and H² are conductors extending downward below the separator B', serving to direct the two groups of matrices to the separators B² and B³, which are similar in construction to those above described except 55 that the tongues or inclined surfaces are differently spaced horizontally.

The notches in the matrices are spaced to correspond, and in such manner that the matrices of two fonts descending to the conductor H', are separated and deflected right and left through conductors H³ and H⁴; while the matrices delivered to the separator B³ are in like manner divided into two groups and directed through conductors H⁵ and H⁶.

Thus it is that each of the conductors H³, H⁴, 65 H⁵ and H⁶ receives only the matrices belonging to one and the same font. These conductors are extended downward and deflected laterally, as shown in Fig. 10, in such manner as to deliver the matrices of the respective fonts between the feed screws E, E, 70 by which they are delivered along the ordinary distributor-bars D', D², D³, D⁴ and D⁵, by which they are finally delivered to the channels of the magazines. 75

It will be observed that separators constructed on my plan will operate equally well on thick and thin matrices, and that matrices of all thicknesses commonly employed may be divided by the one separator. It is also 80 to be observed that the structure permits the use of matrices having the same marginal form and size, except as to the notches therein, so that it is available in connection with the regular commercial matrices now in common use. 85

Having described my invention, I claim and desire to secure by Letters Patent:

1. In a line-casting machine, a matrix separator having reversely inclined overlapping surfaces, substantially as shown; whereby it is adapted to deflect passing matrices right or left, according to form. 90

2. In combination with matrices containing variant notches, a fixed deflector having oppositely inclined overlapping surfaces to deflect the passing matrices, substantially as shown. 95

3. In combination with a series of variously notched matrices and means for guiding them endwise to a separator, a separator having tongues with oppositely inclined surfaces adapted to enter the notches, substantially as shown; whereby a matrix deflected by a surface inclined in one direction, is prevented from encountering the oppositely inclined surface. 100

4. The combination of a series of matrices notched substantially as described, means for guiding them, and successive separators arranged in the path of the matrices, each having reversely inclined surfaces substantially as shown; whereby the matrices are divided into two groups and these groups again divided. 110

5. In combination, two parallel magazines having correspondingly arranged channels, a distributor adapted to release corresponding matrices for the two magazines at a common point, an intermediate deflector arranged to 120 separate the matrices laterally according to font, and means for guiding the separated matrices to the corresponding channels of the respective magazines.

6. A conductor through which matrices for two magazines are delivered, means located in the path of the matrices for separating those of one magazine from those of 125

the other, and two conductors on opposite sides of the separating means to receive the matrices, said conductors having their delivery ends arranged in a common vertical plane one over the other; whereby they are adapted to deliver the matrices to corresponding channels of two magazines.

7. A series of matrices having variously arranged transverse notches in one end, in combination with a stationary separator

having upright tongues with reversely inclined surfaces, substantially as described.

In testimony whereof I hereunto set my hand this twenty fifth day of January, 1908, in the presence of two attesting witnesses.

15

JOHN R. ROGERS.
